UNITED STATES PATENT OFFICE.

EDMOND PIERRE BAVILLE, OF BRUSSELS, BELGIUM, ASSIGNOR TO JULIEN PONTY, OF SAME PLACE, AND HENRY HOWARD, OF COVENTRY, R. I.

MACHINE FOR TURNING BOLTS.

SPECIFICATION forming part of Letters Patent No. 361,571, dated April 19, 1887.

Application filed October 27, 1886. Serial No. 217,319. (No model.)

To all whom it may concern:

Be it known that I, EDMOND PIERRE BAVILLE, of Brussels, in the Kingdom of Belgium, have invented certain new and useful Improvements in Machines for Turning Bolts, of which the following is a specification.

This invention consists in certain features of novelty, which are particularly pointed out in the claims, being first fully described with reference to the accompanying drawings, in which—

Figure 1 is a view showing the greater portion of the machine in elevation, the cutter-heads being shown in vertical section. Fig. 2 is a view showing the machine in front elevation. Fig. 3 is a view showing in detail the automatic unclutching mechanism. Fig. 4 is a plan view of the table or bed of the machine and of the uppermost cutter-head secured thereto. Fig. 5 is an axial section of one of the cutter-heads on a larger scale. Fig. 6 is a plan view of the same. Fig. 7 is a section showing in detail the method of securing the cutting-tools in place. Fig. 8 is an axial section of portions of several cutter-heads having axial perforations for centering the bolt (shown in elevation) and supporting it against the strain of the cutters.

This invention relates, first, to means for securing the several cutters within their respective heads; secondly, to the means for supporting a number of separate and distinct cutter-heads in such manner that the end of the blank as it protrudes from one cutter-head comes into position to be operated upon by the next, and so on in succession until it has reached the last cutter-head of the series, when it will be in such position as to be acted upon by all of them simultaneously; thirdly, to the means for centering the bolt and sustaining it against flexure from the strain put upon it by the several sets of cutters; and, lastly, to the means for revolving the bolt, feeding it forward to the cutters, withdrawing it when the cutting has been completed, stopping the machine for removing the completed bolt and replacing a fresh blank, and other details, which will appear herein-after.

So far as the means for holding the cutting-tools and centering the bolt are concerned, all

of the several cutter-heads employed in this machine are identical, so that a description of one will suffice for all.

A represents a plate or disk which constitutes the body of the cutter-head, and from the upper side of which projects a hub or boss, A', both the disk and the hub being perforated, as at x, for the passage of the blank b. This hub is provided on its upper side with a number of grooves or slots corresponding to the number of cutters which it is desired to employ, said slots being slightly tangential with respect to the eye x of the disk and hub, as seen in Fig. 6, and inclined relative to the axis of the said eye, as seen in Fig. 7. In each of these slots is placed a cutter, B, which is clamped and held firmly by a set-screw, B', the head of which fits in a notch or recess formed in the periphery of the hub A'. The working extremities of these cutters project into the eye of the hub, the stem of the blank being turned down by slowly inserting it between the extremities of said cutters and revolving it by mechanism hereinafter described.

On the under side of the plate A of the upper cutter-head are formed any desired number of bosses or projections A'', each of which is formed with a screw-threaded socket for engaging the correspondingly-screw-threaded end of a stem, D, as shown in Fig. 5, or these sockets may extend completely through said plate, as shown in Fig. 1, the object in either case being simply to support said stems and hold them firmly in positions parallel to the axis of the eye x. The plate A of each of the other cutter-heads is correspondingly perforated, (the perforations being without screw-threads,) the stems being passed through said perforations, and the several cutter-heads secured at the desired distances asunder by means of clamping-screws C. The cutters in the successive cutter-heads approach closer and closer to the axis of the eye x, so as to produce shoulders on the stem of the bolt, as shown in Fig. 8, the cutters in the last cutter-head being made to extend entirely to the said axis, and shaped so as to give the extremity of the stem the desired rounded shape, as shown in Fig. 1.

In order to sustain the stem of the bolt against the strain to which it is necessarily

subjected, the eye through each plate A is made of conical shape for the reception of a bushing-sleeve, a, whose exterior is of a corresponding conical shape, and whose interior 5 is cylindrical and of such size as to fit snugly that portion of the stem which was reduced in size by the cutters carried by the plate in which said sleeve is fitted, as illustrated in Fig. 8. The bolt b is supported, fed forward to the 10 cutters, and revolved by the mechanism now to be described.

The frame of the machine consists of a base, F, and a heavy arm, G, rising from the table E, in which the upper cutter-head is secured. 15 Projecting from the arm G are two horizontal bracket-arms, H H', which are provided with concentric perforations for receiving and guiding a cylindrical spindle, X, the lower end of which is provided with a head or chuck, i, so 20 constructed as to receive the head of the bolt to be turned, and made removable, so as to be replaced by others adapted to receive bolt-heads of any particular construction. This spindle passes through an eye formed through 25 a beveled pinion, I, to which it is secured by a spline and groove, so as to be capable of moving freely longitudinally independently of said pinion, but incapable of independent rotary motion. Gearing with the pinion I is a 30 similar pinion, I', secured to one extremity of a shaft, U, suitably journaled near one end in the arm G and near the other in a bracket-arm, G', fixed removably thereto by means of bolts. Journaled loosely upon this shaft is a 35 band-pulley, K, to which is applied the power for driving the entire machine, said pulley having fixed thereto or formed therewith one half, k, of a clutch, the outer half, k', of which is fixed to the shaft U by a spline and 40 groove, as shown in Fig. 3, so as to render the two incapable of independent rotation, but enable the one to move freely upon the other in a longitudinal direction. By this means it will be seen that when the two members of 45 the clutch are in engagement with each other the spindle X will be rotated in its bearings, it being at the same time moved downward by the mechanism now to be described.

T is a horizontal lever fulcrumed to the top 50 of the arm G of the frame of the machine, and connected with a swivel, X'', turning in the top of the spindle X, through the medium of a link, X'.

To depress the spindle X, the end of the lever 55 to which it is connected is depressed, for which purpose it is connected by a link, S', to the upper extremity of a rack-bar, S, which latter is maintained in vertical position and guided in its movement by brackets P' P'', its teeth 60 being engaged by the teeth of a small pinion (shown by dotted lines only in Fig. 1) fixed to a shaft, Q', turning in bearings in suitable brackets projecting from the frame of the machine. Fixed to this shaft Q', by a spline 65 and groove in the ordinary way, is one half, Q, of a clutch, the other half of which is fixed to or formed integrally with a worm-wheel, O,

journaled loosely upon said shaft and engaged by a worm, N', on one end of a shaft, N, the other end of which shaft is connected by a universal joint, N'', to a short shaft, M, turning in a bearing, M', and carrying a pulley-wheel, L', which is driven by a belt or cord, L'', from a pulley-wheel, L, secured to the shaft U, already referred to. By this means it will be 75 seen that when the two members of the clutch O Q' are in engagement the shaft Q will be rotated, thereby causing the rack-bar S, and consequently the spindle X, to descend. When the two members of this clutch are not in engagement, said shaft may be turned in either 80 direction by means of a hand-wheel, R, secured to it, whereby the rack-bar S may be raised or lowered for bringing the parts to operative position much faster than it is raised 85 or lowered by the worm-gear, the latter being intended more especially for slowly feeding the bolt to the cutters.

For automatically arresting the descent of the spindle X when it has reached the limit 90 which it is desired to put upon its downward movement, a finger or roller, s, carried by the rack-bar S, comes in contact with the upper inclined end of a lever, m, which is pivoted to a suitable fixed bracket and provided with toes 95 for entering the circumferential groove in the sliding member of the clutch O Q', whereby shaft Q is freed from the influence of the worm-gear and permitted to turn freely in its bearings in either direction. A counter-weight, 100 T, secured to the lever T, then causes said lever to rock on its fulcrum, elevating the rod S and spindle X. As the weighted end of this lever descends it comes against a block, Z', secured adjustably to a rod, Z, which latter works at its upper part through an eye formed in the end of a pin, t, swiveled to the lever T, and is connected at its lower extremity by a link, V', to the vertical arm of the frame. This link is of such length and 105 is so situated as to rest constantly against the upper inclined end of a lever, V, which lever is fulcrumed to a bracket, g, projecting from the arm G of the frame, and is bifurcated at its lower end and occupies the circumferential groove in the sliding sleeve k' of the clutch, 110 already referred to. By this means the descent of the weighted end of the lever is made to stop the entire machine. When the new blank has been placed in the chuck i, the hand-wheel R is turned to lower the rod S, which 115 will elevate the weighted end of the lever T and free the clutch-lever V from its constraint. The sliding member k' of the clutch is then forced into engagement with the loose member 120 by a spring, v, contained in a socket in the arm G, and bearing outward against a shoulder formed on a pin, v', which latter bears against the lever V.

Having described my invention, the following is what I claim as new therein and desire to secure by Letters Patent:

1. The combination, with the spindle of a metal-turning machine, of a series of cutter-

- heads, the cutters of one head being projected closer to the axis of said spindle than the cutters of the next adjacent head, substantially as set forth.
5. 2. The combination, with the spindle X and the series of cutters so arranged as to successively reduce the stem of the bolt, of the plates to which the said cutters are secured, having eyes or perforations successively decreasing in size, in the manner and for the purpose set forth.
3. The combination, with the spindle and the upper cutter-head having the sockets, substantially as described, of the pins D, secured in said sockets, and the lower cutter-heads perforated for the passage of said pins and provided with clamping-screws, substantially as set forth.
4. The combination, with the spindle of a metal-turning machine and means for turning it, of a lever with which it has swivel connection, a rack-bar connected to said lever, a pinion gearing with said rack-bar, a shaft to which said pinion is secured, and a wheel for turning said shaft, substantially as set forth.
5. The combination, with the spindle X and means for rotating it, of the lever T, with which it has swivel connection, a counter-balance, a rack-bar, S, connected to said lever, a pinion gearing with said rack-bar, a drive-wheel, a clutch for connecting said drive-wheel and pinion, and a trip on the rack-bar for shifting the clutch, substantially as set forth.
6. The combination, with the spindle, a lever to which it is connected, and a counter-balance for elevating said spindle, of suitable gearing for rotating said spindle, a clutch connecting said gearing with the driving-gear, and a trip actuated by the lever when moved by the counter-balance for disconnecting said clutch, substantially as set forth.
7. The combination, with the spindle X and means for rotating it, of the counterbalanced lever T, to which it is connected, the rack-bar S, also connected to said lever, the pinion gearing with said rack-bar, the driver member O of the clutch, the sliding member Q, the operating-lever m, and the trip s, all constructed and arranged to operate substantially as set forth.
8. The combination, with the spindle and rack-bar having suitable connections, compelling them to rise and fall in unison, of the pinion gearing with said rack-bar, the shaft to which said pinion is secured, the hand-
- wheel R, and one member of the clutch, also secured to said shaft, and the other member of the clutch having means for driving it, substantially as set forth.
9. The combination, with the spindle, the 60 gearing for driving it, the driving-pulley of the machine, and a clutch for connecting said pulley and driving-gear, of a counterbalancing device for elevating said spindle, and a trip operated by said counter-balance for shifting 65 the clutch, substantially as set forth.
10. The combination, with the spindle X, the gear-wheel I, connected thereto by spline and groove, the gear-wheel I', gearing with wheel I and secured to the shaft U, the sliding member k' of the clutch, also secured to said shaft by spline and groove, the pulley K, and the other member, k, of the clutch secured thereto, of the spring-actuated lever V, the lever T, having connection with the spindle X, the weight T', secured to said lever, and the rod Z, depressed by said lever T and engaging the lever V, substantially as set forth.
11. The combination, with the spindle X, the driving-gear, and the clutch for connecting 80 said gear with the driving-pulley of the machine, of the weighted lever T, the pin t, swiveled thereto, the rod Z, passing through an eye in said pin and having the block Z', the link V', connecting the lower end of the 85 rod with the frame, and the spring-actuated lever V, all constructed and arranged to operate substantially as set forth.
12. The combination, with the spindle, means for depressing it, a trip for unclutching 90 its feeding mechanism and arresting its descent, of a counter-balance for elevating it, a clutch for connecting the main driving-pulley with the working-shaft of the machine, and a second trip actuated by said counter- 95 balance for shifting said clutch and arresting the machine, substantially as set forth.
13. The combination, with the spindle, the shaft U, and suitable gearing between them, of the pulleys L L', belt L'', shafts M and N, 100 having the universal joint N'', and mechanism for depressing said spindle actuated by the rotation of the shaft N, substantially as set forth.

In testimony whereof I have hereunto set 105 my hand.

EDMOND PIERRE BAVILLE.
